WEFT BOBBIN

Richard Greenleaf Turner, Worcester, Mass., assignor to Crompton & Knowles Loom Works, Worcester, Mass., a corporation of Massachusetts

Application December 16, 1935, Serial No. 54,649

10 Claims. (Cl. 242—120)

This invention relates to improvements in weft bobbins for carrying large capacities of yarn and it is the general object of the invention to form such a bobbin so that it may be wound on the ordinary spindle winding machine and then if desired used in a spindle shuttle.

Heretofore it has been customary to make bobbins with round barrels so that the weft package is circular in cross section with a height equal to its width. It has been proposed heretofore to provide bobbins the barrels of which are so formed that the weft package in transverse cross section has a greater width than height to permit such bobbins to be used in a loom without increasing the shed lines, thereby decreasing the number of weft replenishments necessary, either automatically or by hand. In such bobbins, however, the barrels have been formed of thin material, such as wood or plastic composition, and in order to attain requisite strength the barrels have been solid in cross section. As a result of this construction it has been necessary to wind the bobbins on a type of winder having a bobbin holder especially adapted to fit the butt of the bobbin and without the usual spindle. Many winding machines have a spindle which projects upwardly through the barrel of the usual bobbin, but in such machines it is not possible to wind bobbins having flattened solid barrels as heretofore constructed. It is an important object of my present invention to provide a bobbin the barrel of which shall be made of a pair of spaced members which within their overall outline will approximate the end sectional dimensions of the flat barrel bobbin, but have these parallel sections spaced so that the spindle of the ordinary winding machine may lie between them.

When used in shuttles flat bobbins as heretofore constructed have required a special form of holder. Many non-automatic shuttles are provided with a spindle hinged to the shuttle body and elevated to permit removal of an exhausted bobbin. The solid flat bobbin barrels of the type heretofore constructed cannot be used with a spindle type of shuttle, and it is a further object of my invention to adapt the weft carrying barrel for use with the ordinary spindle shuttle.

When the spindle of the ordinary shuttle is raised it moves the butt of the bobbin away from holding clips which are rigid with the shuttle and serve normally during weaving to prevent end play of the bobbin relatively to the spindle. It is another object of my present invention to modify the head of the bobbin to present guiding or positioning areas having a definite relation with

respect to the width of the weft package and form the clips or other part of the shuttle to cooperate with these areas in positioning the flattened bobbin correctly in the shuttle so that the narrow dimension will be vertical. 5

Bobbins ordinarily used in weft replenishing looms have butts provided with steel rings and it is another object of my invention to provide a weft barrel formed of wire which can be held to the bobbin butt in any approved manner, such as by welding to the steel rings. The barrel defining wires can be located in longitudinal grooves in the periphery of the bobbin butt to prevent angular displacement of the barrel relatively to the butt, and the rings will lie in the usual concentric grooves extending around the outside of the butt to prevent endwise movement of the barrel secured to said rings. By the provision of a flattened area on the bobbin butt the latter can be placed in the shuttle with the wires forming the barrel disposed in horizontal relation to thereby place the weft package with its width or long transverse dimension horizontal to extend into a previously unused part of the warp shed. 15 20 25

It is another object of my invention to form the tip end of the bobbin barrel with an eye integral with, or rigid with respect to the wire of which the barrel is formed, said eye to receive a spindle to help support the bobbin. 30

With these and other objects in view which will appear as the description proceeds, my invention resides in the combination of parts hereinafter set forth.

In the accompanying drawing, wherein a convenient embodiment of my invention is set forth, 35

Fig. 1 is a diagrammatic view showing a winding spindle having the preferred form of my approved bobbin applied thereto,

Fig. 2 is a section through a shuttle having the preferred or automatic form of my improved bobbin carried thereby and indicating diagrammatically the shed lines of the loom warp, 40

Fig. 3 is an enlarged detailed plan of the bobbin taken in the direction of arrow 3, Fig. 2,

Fig. 4 is an end elevation in the direction of arrow 4, Fig. 3,

Figs. 5 and 6 are horizontal and vertical sections, respectively, on lines 5—5 and 6—6, respectively, of Fig. 4,

Fig. 7 is a transverse section on line 7—7 of Fig. 3,

Fig. 8 shows a modified form of bobbin butt, adapted for use with a spindle type shuttle,

Fig. 9 is a vertical transverse section on line 9—9 of Fig. 8,

Fig. 10 is a plan view taken in the direction of arrow 10, Fig. 9, and

Fig. 11 is an end view taken in the direction of arrow 11 of Fig. 3.

5 In the description that follows I have shown my invention applied to automatic and non-automatic bobbins, the automatic bobbin being shown as the preferred form. As seen in Fig. 1 the winding spindle 20 may be rotatably mounted in frame 21 of the winding machine and have a tang 22 extending outwardly therefrom to support the bobbin. By means of a pulley 23 the spindle is rotated and yarn feeding mechanism not shown supplies the weft to be wound on the 10 bobbin as the spindle rotates. This spindle may be of the usual kind and of itself forms no part of my present invention.

The bobbin B comprises a spindle receiving head 25 which may be of wood or plastic composition and has mounted thereon the usual three spaced rings 26 to be received by spring clips 27 in a shuttle 28. The shuttle is somewhat wider than those customarily employed, although its height will be of the usual dimension.

25 The head 25 may have a square outer butt 30 having upper and lower preferably flat parallel surfaces 31 and 32, respectively, see Fig. 4, which may assist in the transferring operation in a manner similar to that set forth in my co-pending application Serial No. 53,457, filed December 9, 1935. That part of the head extending to the right of the square butt end as viewed in Fig. 3 may have parallel longitudinally extending opposite grooves 33 which extend under the rings 35 to receive the holding ends 34 and 35 of a wire 36 having spaced weft supporting parallel strands 37. The latter, as shown in Fig. 3, are separated by a space 38 depending upon the desired width of the package of weft, said space being sufficient 40 to receive the tang 22 of the winder. The ends 34 and 35 may be welded to the undersides of the rings as indicated at 39 and the rings are received by peripheral grooves 29 one of which is indicated in Fig. 6 by removal of the corresponding ring. By this construction it will be seen that rotation of the rings about the butt is prevented by mutual cooperation of the ends 34 and 35 with the grooves 33, and that endwise movement of the wire 36 relatively to the butt is 45 prevented by the grooves 29. The wired structure is therefore held effectively in given angular relation with respect to the square butt 30, the line joining the two wires being preferably parallel to the surfaces 31 and 32, as indicated in 50 Fig. 4.

The wire 36 is bent between the strands 37 to form a tip 40 having a loop 41 to provide a guide eye for a spindle, as shown in Fig. 11. The center of the eye 41 preferably lies on the axis of a 55 spindle bore 42 in head 25 and parallel to strands 37.

The strands 37 may be bent as at 48 if it is desired to have the space between those parts of the wires defining the weft carrying part of the 60 bobbin of less width than the distance between ends 34 and 35.

65 Shuttle 28 has a front wall 50 with a slot 51 to receive positive and negative electric weft detector prongs 52 and 53, respectively, which ordinarily are kept insulated from each other by a sufficient mass of weft for continued weaving but which are electrically connected by the front strand 37, as shown in Fig. 3, when weft exhaustion approaches.

70 As shown in Fig. 4 the wire 36 and its strands

37 define weft supporting structure having a width considerably greater than its height so that the wound mass of weft W will be flattened on its upper and lower surfaces, but will have a width considerably greater to permit the winding of an 5 increased amount of weft.

The modified form of the invention shown in Figs. 8, 9 and 10 relates to a bobbin adapted for use in a spindle type of non-automatic shuttle. As shown in Fig. 8 a shuttle 60 has a shuttle spindle 61 pivoted thereto as at 62 and can swing from the normal position parallel to the shuttle axis upwardly in usual manner to permit the removal of an exhausted bobbin and its replacement by one having a full weft supply. The 10 modified bobbin may be as set forth in Figs. 9 and 10 and comprises a head 65 of plastic composition, such as a phenol condensation product, having a cylindrical shoulder 66 and a butt 67 the bottom surface of which may be flat as at 68. 15 The top of the butt may also be flat so that in general outline its shape will conform to that in Fig. 9, this construction permitting the bobbin to be inserted.

The bobbin barrel in this form may have a wire 25 70 with parallel strands 71 the left ends of which as indicated in Fig. 10 are bent and embedded in the head 65. The latter has a bore 74 which receives the tang 22 and shuttle spindle 61, and disposed with its axis parallel to the strands 71 30 as in the preferred form. The tip of the modified bobbin is similar to that of the preferred form.

It is customary in shuttles of the type illustrated in Fig. 8 to supply retaining clips 75 having 35 invent ends 76 which lie to the right of some part of the head 65 as viewed in Fig. 8 for the purpose of preventing the bobbin from sliding endwise off the spindle 61 when the shuttle is checked. I retain this feature in the present 40 instance, but in addition supply each clip with a floor 78 against which the corner 79 of the butt 67 rests, see Fig. 9. The aligned floors 78 45 position the lower surface 68 so that the bobbin is held with the wire strands 71 in substantially horizontal alignment for the purposes already described in connection with the preferred form of the invention.

From the foregoing it will be seen that I have provided a simple form of bobbin so constructed 50 that the mass of weft carried thereby may have a width greater than the height and that the supporting parts of the bobbin which hold the mass of weft are such as to permit use with the usual winding or shuttle spindle. In both forms 55 the tip end of the bobbin is formed to receive the end of a spindle or tang 22 to avoid vibration in the winding operation.

Since the barrel is formed of metallic wire, the 60 bobbin is readily adaptable to use with an electric weft detector. In the preferred form for automatic use the ordinary rings which hold the bobbin in the shuttle may be secured to the barrel forming wires as by welding, although I do not wish to be limited to this particular means of 65 securing the butt ends of the barrel wire in fixed relation with respect to the head. In the modified form the shuttle carried bobbin retaining clips may be formed so as to cooperate with parts 70 of the bobbin head or butt to maintain the width of the weft mass parallel to the width of the shuttle, although I do not wish to be limited to accomplishing this result necessarily by the use of clips 75.

Having thus described my invention it will 75

be seen that changes and modifications may be made therein by those skilled in the art without departing from the spirit and scope of the invention and I do not wish to be limited to the details 5 herein disclosed, but what I claim is:

1. In a weft bobbin to cooperate with a spindle, a head having a spindle bore therethrough, holding metallic rings supported by the head and extending around the bore, a pair of metallic 10 wires extending into the rings and supported by and extending from the head in a direction substantially parallel to the bore axis and located on opposite sides of the latter, and means integral with said wire strands defining an eye 15 concentric with the bore axis and located to receive a spindle.

2. In a weft bobbin to cooperate with a spindle, a head having a spindle bore therethrough, holding metallic rings supported by the head and extending around the bore, a pair of spaced wire 20 strands extending into the rings and located on opposite sides of the bore axis and fixed with respect to and projecting from the head, and means integral with the wire strands defining a 25 spindle eye substantially concentric with the bore axis.

3. In a weft bobbin to cooperate with a spindle, a head having a spindle bore therethrough, metallic rings supported by the head and extending 30 around the axis of the bore, and a pair of wire strands secured to the rings and extending from the head in a direction substantially parallel to the bore axis, said strands lying on opposite sides of the axis.

35 4. In a weft bobbin to cooperate with a spindle, a head having a spindle bore therethrough, holding rings supported by the head and extending around the bore and restrained against movement along the head in a direction parallel to the bore axis, and spaced elongated weft 40 supporting elements extending into the rings and held against angular motion with respect to the head around the bore axis, the elements extending from the head substantially parallel to the bore axis.

45 5. In a weft bobbin to cooperate with a spindle, a head having a spindle bore therethrough, holding metallic rings supported by the head and extending around the bore, a pair of spaced wire strands welded to the rings and extending from the head in a direction substantially parallel to the axis of the bore, and means integral with

the strands defining a spindle receiving eye substantially concentric with the axis of the bore.

6. In a weft bobbin to cooperate with a spindle, a head having a spindle bore therethrough, holding rings supported by the head and extending around the bore, and spaced elongated weft 5 supporting elements extending into the rings and held against angular motion relatively to the head around the bore axis, said elements extending from the head in a direction along the bore axis.

7. In a weft bobbin to cooperate with a spindle, a head having a spindle bore therethrough and having a flattened surface transverse of the bore axis and substantially parallel thereto, holding 15 rings supported by the head and extending around the bore axis, and spaced elongated weft supporting elements extending into the rings and held against angular motion relatively to the head around the bore axis, said elements 20 extending from the head in a direction along the bore axis, a transverse line joining said elements being substantially parallel to said surface.

8. In a weft bobbin to cooperate with a spindle, a head having a spindle bore therethrough, 25 metallic elements supported by and extending around the head, and a pair of metallic members connected to the elements and extending from the head in a direction along the axis of the bore, said members lying on opposite sides 30 of the axis.

9. In a weft bobbin to cooperate with a spindle, a head having a spindle bore therethrough, metallic elements supported by and extending around the head, and a pair of metallic members connected to the elements and extending from the head in a direction along the axis of the bore, said members lying on opposite sides 35 of the axis and being connected to each other at a point remote from the head.

10. In a weft bobbin to cooperate with a spindle and adapted for use in a bobbin changing loom, a head having a spindle bore therethrough and having a flattened area substantially parallel to the bore axis, metallic elements supported by and extending around the head, and a pair of elongated members connected to the elements and held against angular motion relatively to the head around the bore axis, said members extending in the direction of the bore 40 axis and lying on opposite sides of said axis. 45

RICHARD GREENLEAF TURNER.
